[57] CLAIM

The ornamental design for an upright extractor recovery tank, as shown and described.

DESCRIPTION

FIG. 1 is a left side elevational view of an upright extractor recovery tank showing my new design;
FIG. 2 is an enlarged left side elevational view thereof, the right side being a mirror image;
FIG. 3 is an enlarged front elevational view thereof; and,
FIG. 4 is an enlarged top plan view thereof.

The details shown in broken lines are shown for illustrative purposes only and form no part of the claimed design.
